Patented Apr. 26, 1921.

John Johnsen Inventor

By his Attorney

Ivan E. G. Koenigsberg

UNITED STATES PATENT OFFICE.

JOHN JOHNSEN, OF NEW BRIGHTON, NEW YORK.

COMBINED JACK AND CLAMP.

1,376,017.

Specification of Letters Patent. Patented Apr. 26, 1921.

Application filed June 25, 1920. Serial No. 391,700.

To all whom it may concern:

Be it known that I, JOHN JOHNSEN, a citizen of the United States, and resident of New Brighton, in the county of Richmond 5 and State of New York, have invented certain new and useful Improvements in Combined Jacks and Clamps, of which the following is a specification.

This invention relates to improvements in 10 combined jacks and clamps. The object of the invention is to provide a generally improved jack and clamp with particular reference to ease of operation, strength of construction, and facility in interchanging parts 15 for economy in the line of repairs.

Accordingly my invention is embodied in a combined jack and clamp constructed and arranged as hereinafter set forth and as 20 illustrated in the accompanying drawing in

Figure 1 is a vertical central sectional view of a jack and clamp embodying my invention, and

Fig. 2 is a detail view taken on the line 25 2—2 of Fig. 1.

The reference numeral 3 denotes a base, preferably slightly tapered as shown, and providing a substantial solid foot portion 4 adapted to rest upon the ground or the 30 member which supports the jack during the lifting operation. The base is provided with a socket 5, and at right angles to the said socket the base is apertured to receive a screw, bolt, or pin 6 by means of which a hook member or jaw 7 is removably held in 35 said socket.

The jaw 7 has a body portion 8 adapted to fit in said socket and a hook portion 9 turned upwardly or away from the foot portion 4 of the base. The latter is further provided 40 with a smooth bore 30. The numeral 10 designates an interiorly threaded nut which is secured to the base by any suitable means, such for instance as the screws 11.

The numeral 12 denotes in general the 45 lifting member which comprises a screw-threaded stem 13 adapted to be screwed into and out of the nut 10 and which stem slides easily within the smooth bore 30. The member 12 is provided with two integral collars 14 and 15, and the top of the stem is formed with an annular groove 16 above the collar 15. Upon the latter rests a lifting head 17 having a suitable gripping surface 18. The head 17 is securely but rotatably held upon the member 12 by a pin or screw 55 19 which is removably secured to the head and which extends into the said annular groove 16.

The collar 15 is apertured as at 20 and 21 60 for the suitable application of a handle 22.

The numeral 23 denotes an upper hook member or jaw which consists of a jaw 24 having a hook portion 25 similar to the hook portion 9 of the jaw 7, and a clamp 65 portion 26 adapted to fit around the member 12 between the collars 14 and 15. The upper hook member 23 is rotatably and removably held on the stem by means of a clamp member 27 which is secured to the 70 hook member 23 by bolts 28. The two members 26 and 27 form a sleeve or hinge portion 29, as shown in Fig. 2, and whereby the upper hook is held securely on the stem yet is freely rotatable thereon. 75

The use of the apparatus is obvious. It may be used as an ordinary lifting jack by applying the handle 22 to screw the stem out of the nut 10. The fact that the head 17 does not turn with the stem is an obvious 80 advantage. The hook member 23 may be turned upward to assist in lifting an object having a contour or which is so constructed that the hook and the head may both be used to advantage. 85

The apparatus may be used as a clamp by placing the objects to be clamped together between the two hooks 9 and 25. Again, the apparatus may be used to pull together the ends of a cable or rope attached to the hooks 90 after having been passed around the objects to be bound or bundled together.

The advantages of the detailed construction are several. It will be noted that the hooks may be removed and replaced very 95 easily in case one or both should break, for instance, or for other reasons.

The upper hook may be turned around the stem to suit the form of an object to be clamped between the hooks, or the upper 100 hook may be turned upward if so desired. The head is easily removed from the stem, and should the nut 10 or the screw break, either part is easily removed and replaced without it being necessary to discard the 105 entire apparatus.

It is understood that I do not intend to limit my invention to the exact disclosure herein, but that its scope is defined in the appended claim. 110

I claim:—

A combined jack and clamp comprising a

base, a hook member secured to said base to project therefrom in a fixed direction with respect thereto, a nut secured to said base, a lifting member in threaded engagement with the said nut, a lifting head rotatably carried by said lifting member, a plurality of integral collars on the lifting member, a second hook member, means for securing the latter to the said lifting member between the said collars thereon, said second

hook member being rotatably carried by said lifting member and being adapted to be mounted with its hook portion pointing either upward or downward, and means for operating said lifting member.

Signed at New York in the county of New York and State of New York this 24th day of June A. D. 1920.

JOHN JOHNSEN.
